UNITED STATES PATENT OFFICE.

WILLIAM E. THOMPSON AND EMMA E. THOMPSON, OF RANGER LAKE, NEW MEXICO.

CALCULATOR.

1,025,334.

Specification of Letters Patent.

Patented May 7, 1912.

Application filed December 2, 1911. Serial No. 663,559.

To all whom it may concern:

Be it known that we, WILLIAM E. THOMPSON and EMMA E. THOMPSON, citizens of the United States, residing at Ranger Lake, 5 in the county of Chaves and State of New Mexico, have invented certain new and useful Improvements in Calculators, of which the following is a specification.

This invention relates to machines for 10 mechanically performing the mathematical operation of addition, and it has for its object to provide a machine of this kind which can be easily and rapidly operated, and which is devoid of complicated parts to get 15 out of order.

The invention also has for its object to provide a novel and improved key-operated mechanism for actuating the registering devices, together with certain improved structural details to be hereinafter described and claimed.

In order that the invention may be better understood, reference is had to the accompanying drawings forming a part of this 25 specification, in which drawings—Figure 1 is a front elevation of the machine. Fig. 2 is an end elevation of the registering mechanism, the casing inclosing the same being shown in section. Fig. 3 is a section on the 30 line 3—3 of Fig. 2. Fig. 4 is a bottom plan view of the key-actuated arms to be herein-after described. Fig. 5 is a plan view of the registering mechanism. Fig. 6 is a sectional detail of a portion of said mechanism. Fig. 35 7 is a perspective view of a modified structure.

Referring specifically to the drawings, 10 denotes a suitable casing which incloses the mechanism. In the front wall of the casing 40 is a sight opening 11 through which the results are displayed. The front of the casing also has a forward bottom extension 12 in the top of which are apertures through which the stems 13 of the several keys extend. It will be noted that two groups of 45 keys are provided. The group to the right contains nine keys, these keys being the digit keys, and being numbered from 1 to 9, respectively. The group to the left contains

four keys. These keys represent units, tens, 50 hundreds, and thousands, respectively. The number of keys in the last-mentioned group may be increased if the machine is designed for greater sums than thousands.

Suitably supported within the casing 10 55 is a stationary shaft 14 on which are loosely mounted, for independent rotation thereon, four gear wheels, 15, 16, 17 and 18, respectively. These wheels, it will be noted, correspond in number to the group of keys 60 at the left of the machine, and they may be termed units, tens, hundreds, and thousands wheels. To each wheel is rigidly connected, so as to turn therewith, a ratchet wheel 19, 65 with spacing washers therebetween.

To the shaft 14 is pivoted a lever 20 and below said lever is a supporting frame 21 to which are pivoted arms 22 connected by rods 23 to the levers 24 of the respective digit keys, said levers being fulcrumed intermediate their ends on a rod 25. The arms 22 are of different lengths, and their pivots 22^a are in alinement. The lever of the digit key 1 is connected to the shortest arm, the lever of the digit key 2 to the next arm, and 70 so on throughout the entire series, the lever of the digit key 9 being connected to the longest arm. The point of attachment of each rod 25 to the arms 22 coincides with the pivot of the next succeeding shorter arm. 75 Thus, the rod which connects the lever of the digit key 9 to the longest arm is opposite the pivot of the arm to which the lever of the digit key 8 is connected.

It will be evident from the foregoing that 85 the arms swing through arcs of different magnitudes when the digit keys are operated, the arm to which the digit key 9 is connected making the greatest swing, and the arm to which the digit key 1 is connected 90 making the smallest swing. The motion of the arms 22 is transmitted to the lever 20 by a stem 26 pivotally connected at one of its ends to the free end of said lever and depending therefrom, and having its other 95 end widened and formed with a knife edge resting on the free ends of the arms 22, said ends being in alinement and having notches,

which latter are also in alinement to form a groove 27 in which the knife edge of the stem 26 seats. Inasmuch as the arms 22 have a variable swing, it will be evident that the lever is also given a variable swing when the digit keys are operated. Thus, a minimum swing is given the lever when the digit key 1 is operated, whereas a maximum swing is given the lever when the digit key 9 is operated.

A mechanism to be presently described imparts motion to the wheels 15, 16, 17 and 18, and by the variable swing of the lever 20 said wheels are moved the desired number of steps. When the digit key 1 is operated, the wheels move one step, when the digit key 2 is operated, the wheels are moved two steps, and so on, the number of steps progressing by one until the key 9 is reached which moves the wheels nine steps.

A spring 28 is connected to the lever 20 for the purpose of restoring the same to its normal position after the digit keys have been operated.

The following mechanism transmits the motion of the lever 20 to the wheels 15, 16, 17 and 18: To the pivoted end of the lever 20 is rigidly connected a fork, the branches 29 of which are also pivotally connected to the shaft 14. The fork branches carry a housing 30 to which is pivoted at one of its ends on a transverse rod 31 carried by the housing, an arm 32. On the rod 31 is pivotally mounted a spring-pressed pawl 33 having in its bottom edge a shoulder 33^a engaged by a stud 33^b carried by the arm 32. The pivoted end of the arm also has a stud 34 over which fits one end of a coiled spring 34^a, the other end of which abuts against the top of the housing 30. A pawl and support therefor as herein described is provided for each ratchet wheel 19. The function of the spring 34^a is to swing the arm 32 upwardly so that the pawls will be free of the respective ratchet wheels, this being their normal position. The supporting arm 32 of the pawl of the units ratchet wheel is connected to the units key, the supporting arm of the pawl of the tens ratchet wheel 50 to the tens key, and so on in the same order throughout the series. The connections are such that when any one of the units, tens, etc., keys is depressed, the corresponding pawl is placed in operative position. Thus, 55 when the tens key is depressed, the pawl of the ratchet wheel of the tens wheel is placed in operative position, and then upon depressing, say, the digit key 3, the tens wheel is rotated three steps. The units, tens, etc., keys therefore select the wheels which are to be operated by the digit keys 1 to 9.

The connection between the units, tens,

etc., keys with the arms 32 is made by means of wires 35 connected at one of their ends to said keys, and at their other ends to loops 36 connected to the free ends of the arms. The shaft 14 passes loosely through the loops, and the free ends of the arms have slots 37 through which loosely pass pins 38 connecting the loops to the arms. Upon depressing one of the units, tens, etc., keys, the arm 32 to which said key is connected swings down until it is stopped by the shaft 14, and the pawl carried by said arm then engages the corresponding ratchet wheel 19, whereupon the mechanism is ready for the operation of the lever 20. The slots 37 allow the connections 38 to move back and forth, and permit the motion produced by the lever 20.

It will be noted that all the wires 35 and loops 36 do not extend in a straight line to the keys, in view of which the loop will have a slight sidewise movement when it is swung downward, which, however, will not be great enough to interfere with or prevent the proper operation, but if more than four keys are employed, an auxiliary lever 39 is employed for each additional key. This lever has one of its ends connected by a link 39^a to the key, and has connected adjacent to its other end the wire 35, the point of connection being located directly beneath the shaft 14, so that the wire runs in a straight line upward to the connection with the arm 32. Fig. 7 of the drawing illustrates this mechanism.

In mesh with the respective gear wheels 15, 16, 17 and 18 are pinions 40, 41, 42 and 43. The pinion 40 is fast on an arbor 44 carrying a dial 45 provided with a numbered face, the numbers running from zero to 9 and being arranged in a circular series. This is the units dial. Tens, hundreds, and thousands dials 46, 47 and 48 are also provided, they being arranged concentrically and superposed on the dial 45, and each succeeding dial being smaller in diameter than the preceding one, so that the numbers of the several dials may be visible through the sight opening 11. The dial 46 is carried by the arbor 49 of the pinion 41, the dial 47 by the arbor 50 of the pinion 42, and the dial 48 by the arbor 51 of the pinion 43. The pinions are fast on the arbors, and the latter, with the exception of the arbor 51, are hollow and arranged one within the other, the arbor 51 being at the center. Each arbor turns independently of the others, and each pinion has ten teeth.

The transfer mechanism for transmitting motion from the gear wheel 15 to the gear wheels 16, 17 and 18 consists of the following elements: In mesh with the gear

wheel 15 is a pinion 52 which is fast on a shaft 53 on which is also fast a wheel 54 having one tooth. The pinion 52 has ten teeth. The toothed wheel 54 is so positioned that it comes in mesh with the gear wheel 16 every time the pinion 52 makes one complete revolution. It will therefore be evident that for every ten steps of the gear wheel 15, the gear wheel 16 makes one step. A similar mechanism transmits the motion of the gear wheel 16 to the gear wheel 17, and the motion of the latter to the gear wheel 18. The shaft of the transfer mechanism between the gear wheels 16 and 17 is indicated at 55, and that of the transfer mechanism between the gear wheels 17 and 18 is indicated at 56. Thus it will be seen that each dial when passing ten steps will register its proper value on the next higher dial. The shafts 53, 55 and 56 project through the front wall of the casing and on the projecting end of each shaft is fixed a small pointer or hand 57 by means of which the shafts may be turned back, beginning with the shaft 53, to return the toothed wheels and at the same time the gear wheels to zero position. Index marks 58 on the casing indicate the position to which the pointers have to be turned to place the parts in zero position. The thousands gear wheel 18 is set back to zero by a pointer 59 on a shaft 60 which carries a pinion 61 in mesh with said gear wheel. Overthrow preventers are also provided, the same comprising spring-pressed pawls 62 engageable with the gear wheels 15, 16, 17 and 18.

Assuming it is desired to add 346, 254, and 520, the operation of the machine is as follows: Beginning at the first number, press the units key and the digit key 6, whereupon the sight opening 11 displays 0006. Then press the tens key and the digit key 4, whereupon the sight opening displays 0046. Then press the hundreds key and the digit key 3, whereupon the sight opening displays 0346. The next numbers are registered by pressing the proper units and digit keys, the operation being continued until all the numbers have been registered, whereupon the sum of the several numbers, to wit, 1120, is displayed at the sight opening. The machine is then set back to zero and is ready for the next operation. The sum can also be found by adding all the units figures, then the tens, etc.

It will be understood, of course, that when any one of the gear wheels 15, 16, 17 and 18 has taken ten steps, the result will be transferred to the next higher one in the series. Thus, when 4 is added to 346, the units gear wheel 15 will have taken ten steps, the pinion 52 has been given one revolution, and

the toothed wheel 54 has turned the tens gear wheel 16 one step so that now 350 is displayed at the sight opening. 65

The preferred embodiment of the invention has been shown, but it will be understood that various changes in the structural details may be made without departing from the spirit or scope of the invention. 70

We claim:

1. In a calculator, a plurality of register wheels of different orders, a transfer mechanism for said wheels, pawls for actuating the register wheels, a lever carrying the pawls, pivoted arms arranged to swing through arcs of different magnitudes, a connection between the arms and the lever, keys operatively connected to the arms, and key-operated means for placing the pawls in operative position with respect to a selected register wheel. 75

2. In a calculator, a plurality of register wheels of different orders, a transfer mechanism for said wheels, a key-actuated pawl-and-ratchet mechanism for operating the register wheels, and key-operated means for placing the pawls in operative position with respect to a selected register wheel. 80

3. In a calculator, a plurality of register wheels of different orders, a transfer mechanism for said wheels, a key-actuated pawl-and-ratchet mechanism for operating the register wheels, means for normally holding the pawls in inoperative position, and key-operated means for placing the pawls in operative position with respect to a selected register wheel. 90

4. In a calculator, a plurality of register wheels of different orders, a transfer mechanism for said wheels, means for operating the register wheels, said means including a lever, pivoted arms swinging through arcs of different magnitudes, and keys operatively connected to the arms, and key-operated means for placing the operating means of the register wheels in operative position with respect to a selected register wheel. 100

5. In a calculator, a plurality of register wheels of different orders, a transfer mechanism for said wheels, a key-operated lever having a variable swing, pawls carried by the lever for actuating the register wheels, arms carried by the lever, means on the arms for lifting the pawls into inoperative position, and keys operatively connected to the arms for actuating the same to place the pawls in operative position. 110

6. In a calculator, a plurality of register wheels of different orders, a transfer mechanism for said wheels, a key-operated lever having a variable swing, pawls carried by the lever for actuating the register wheels, arms carried by the lever, studs on the arms

engageable with the pawls, springs engageable with the arms for swinging the latter into position to place the pawls in inoperative position, and keys operatively connected to the arms for swinging the same to place the pawls in operative position.

7. In a calculator, a register wheel, and means for operating said wheel, said means including a lever, a series of pivoted arms 10 of different lengths, a connection between the lever and the arms, and keys operatively

connected to the arms, the point of attachment of said connection to each arm coinciding with the pivot of the next shorter arm in the series.

In testimony whereof we affix our signatures in presence of two witnesses.

WILLIAM E. THOMPSON.
EMMA E. THOMPSON.
